The ornamental design for a calculator for surveying date, as shown.

DESCRIPTION

FIG. 1 is a perspective view from above right of the calculator for surveying date according to our novel design; FIG. 2 is a front view of the calculator for surveying date of FIG. 1;

FIG. 3 is a left side view of the calculator for surveying date of FIG. 1;

FIG. 4 is a rear view of the calculator for surveying date of FIG. 1;

FIG. 5 is a right side view of the calculator for surveying date of FIG. 1;

FIG. 6 is a top plan view of the calculator for surveying date of FIG. 1; and,

FIG. 7 is a bottom view of the calculator for surveying date of FIG. 1.
